(57) **CLAIM**

The ornamental design for a spoiler boost splitter, as shown and described.

DESCRIPTION

FIG. 1 is a top-front-left perspective view of a spoiler boost splitter showing my new design;

FIG. 2 is a bottom-front-left perspective view thereof;

FIG. 3 is a top-rear-right perspective view thereof;

FIG. 4 is a bottom-rear-right perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is an enlarged right side elevational view thereof; and,

FIG. 10 is an enlarged left side elevational view thereof.

The broken lines showing of fasteners in FIGS. 2, 4-6, and 8-10, and the broken lines showing of fastening sections in FIGS. 2, 4-5, and 8 are included for the purpose of showing environmental structure and form no part of the claimed design.
